UNITED STATES PATENT OFFICE.

WILLIAM D. LA RUE, OF PHILADELPHIA, PENNSYLVANIA, ASSIGNOR TO VICTOR TALKING MACHINE COMPANY, A CORPORATION OF NEW JERSEY.

DISPENSING DEVICE.

Application filed November 15, 1921. Serial No. 515,238.

My invention relates to dispensing devices and particularly to devices for dispensing elongated articles which are substantially alike in length and thickness or diameter such, for example, as talking machine styli or needles, whereby a single article is separated or selected from a quantity of like articles loosely stored in a suitable container, and is automatically delivered from said container to the user as occasion for use of one of said devices may arise.

The objects of my invention are to provide a device which may be permanently attached to and form a part of a substantial structure, as for instance a talking machine cabinet, and which is adapted to contain a considerable stock or store of small loose elongated articles, such as talking machine styli; to provide a device which, although so permanently secured to an object, provides means whereby the container itself may be readily separated from a fixed part of the dispensing device and when removed may be replenished with a fresh stock or supply of loose articles to be dispensed thereby; to provide a dispensing device by means of which small articles, such as styli or needles, may be automatically discharged one at a time to a position on a holder, receiver or other suitable receptacle, from which it may be readily picked up; to provide a small dispensing device which will not detract from, but on the other hand will improve the appearance of the whole device on which the same may be mounted; to provide a stylus dispensing device which is so easily operated and which so conveniently dispenses or discharges styli that the user of a talking machine will prefer to use the same rather than to permit loose styli to remain scattered over the top of a talking machine; to provide a device which will deliver an article the ends of which are of different weight with a selected end, as for instance the lighter or smaller end, always pointing in the same direction; and to provide a device which will deliver the articles contained therein one at a time until the supply therein is completely exhausted.

Further objects of my invention will appear in the specification and claims below.

In the drawings forming a part of this specification and in which the same reference

characters are used to designate the same parts.

Figure 1 is a front side elevational view partly in section of the preferred form of my dispensing device;

Fig. 2 is a rear elevational view of the same;

Fig. 3 is a vertical sectional view, in the main, through the device shown in Fig. 1 and showing a separated stylus being carried upwardly to the point where it is discharged from the container to the receiver;

Fig. 4 is a view similar to Fig. 3 but showing the container as having been completely turned to the point where the stylus is discharged therefrom and showing the discharged stylus resting on the receiver;

Fig. 5, in general, is a sectional view on the line 5—5 of Fig. 4;

Fig. 6 is a front view of the device;

Figs. 7 and 8 are detail views showing the construction whereby the styli are delivered with the lighter or sharpened end always pointing in the same direction;

Figs. 9 to 15 inclusive show a modified form of my invention;

Fig. 9 is a front side elevational view thereof, partly in section;

Fig. 10 is a rear elevational view of the same;

Fig. 11 is a vertical sectional view of the same;

Fig. 12 is a view similar to Fig. 11 but showing the device as having discharged a stylus to the receiver;

Fig. 13 is a horizontal sectional view on the line 13—13 of Fig. 12;

Fig. 14 is a front view of the device;

Fig. 15 is a rear view of the same;

Fig. 16 is a horizontal sectional view, somewhat similar to Fig. 5, of another modified form of my device; and

Fig. 17 is a similar horizontal sectional view of a further modification.

In the drawings my invention is shown as adapted and arranged for the purpose of dispensing talking machine styli. In Figs. 1 to 8 the device is shown as permanently mounted upon a base 1 which may be, and preferably is, a portion of a talking machine cabinet, adjacent the turntable. The device is preferably secured thereto by screws 2 extending through the feet, 3, 3, at the ends

of the legs 4, 4, which extend downwardly from a curved support or saddle 5. The interior surface of said saddle is preferably arc-shaped and fits against the surface of the outer cylindrical member 6, to which the saddle 5 is rigidly and permanently secured, as by brazing or soldering. One end, 7, of said outer member 6 is preferably substantially closed. Extending outwardly from the center of said closed end 7 is a projection 8 provided with a cylindrical bearing surface 9 coaxial with the axis of the cylindrical inner surface of the member 6.

Said member 6 is also provided with a slot 10 extending parallel to the axis of the cylindrical member 6, and the lower edge 11 of the slot 10 is preferably slightly beveled upwardly and inwardly to form a shoulder over which a stylus, or other article dispensed by the device, is delivered as the device is operated.

Mounted upon the front side of the outer member 6 and extending outwardly and downwardly from the lower edge or shoulder 11 of the slot 10, is a shelf or receiver 12, the outer free end 13 of which is upturned to hold and retain the article delivered thereto through the slot 10.

The closed end 7 of the outer member 6 is also provided with an arch-shaped slot 14 also disposed concentrically to the axis of the cylindrical bearing surface 9.

Mounted within the member 5 is the container 15, the same being preferably cylindrical in shape and having one end 13 permanently closed. Extending from the middle of the closed end is a stem or journal 17 concentric with the axis of the container 15 and adapted to fit smoothly within the bearing 9 in the projection 8 of the member 6. The outer end 18 of the stem 17 is preferably screw-threaded and provided with a nut 19 which, when threaded over the end 18, seats squarely against the shoulder 20 between the threaded end 18 and the journal 17. In this manner the container 15 is mounted to freely turn within the member 6 upon the bearing 9, and is restrained from moving longitudinally in the bearing 9.

The other end of the container 15 is closed by head 21 removable therefrom and snugly fitted into the otherwise open end of the container 15. Said head 21 is preferably provided with an outwardly extending knurled flange 22. A pin 23, outwardly extending from the cylindrical portion of the head 21, which fits within the container 15, is adapted to cooperate with a bayonet slot 24 extending inwardly from the edge at the open end of the container 15, said pin 23 and bayonet slot 24 providing means whereby the head 21 may be secured to and held within the open end of the container 15. The head 21 is also preferably provided with a handle 25 by means of which the container

may be freely turned or rotated on its journal 17 within the member 6.

The permanently closed end 16 of the container 15 is also provided with a stop pin 26 extending outwardly therefrom through the arc-shaped slot 14 in the outer member 6. By means of this construction, when the container is rotated or turned on its bearing in one direction (e. g. clockwise), the engagement of the pin 26 with one end 27 of the slot 14 will prevent the rotation of the container beyond a predetermined position in that direction, and when the container is rotated in the opposite direction (anti-clockwise) the pin 26 will eventually strike against the end 28 of the slot 14 and said end 28 will provide a stop to prevent the rotation of the container in that direction beyond a predetermined point. The length of the said slot 14 is preferably such as to permit the container to rotate through an angle of about 180°.

Extending through the cylindrical surface of the container 15 is a slot 29 extending parallel to the axis of said container. When the container has been rotated in a clockwise direction and the pin 26 is in engagement with the stop 27, the lower edge or shoulder 30 of the slot 29 will be in alignment or flush with the lower edge or shoulder 11 of the slot 10. In the embodiment of my invention shown in Figs. 1 to 8, the slot 29 will be in registration with the slot 10 when the pin 26 bears against the stop 27 at the end of the slot 14. Extending upwardly and inwardly from the lower edge of the slot 29 is a tongue or lip 31. The width of this tongue is made such that only one of the articles to be dispensed by the device will rest on and be supported thereby when the container has been rotated to bring the slot 29 therein almost into registration with the slot 10 in the member 6. When the device is adapted and arranged for dispensing talking machine styli, as shown in the drawings, the tongue or lip 31 should not be wide enough to simultaneously support two styli, when the parts are in the position indicated in Fig. 3. In that position it should form a support upon which but one stylus will rest at a time.

In such a device for dispensing talking machine styli, it is sometimes desirable that the pointed or sharpened end 33 of a stylus 32 shall always point in the same direction as it is delivered from the container to the receiver 12. To accomplish this, the length of the tongue or lip 31 is made substantially one-half of the length of the slot 29 in the container 15, or to be more accurate, substantially one-half of the length of the stylus 32 to be handled and dispensed thereby. In this connection, attention is directed to Figs. 5, 6, 7, and 8. The pointed end of a stylus weighs considerably less than

the opposite end, or considering the stylus as divided lengthwise into two parts of equal length, that half which is provided with the tapered point will weigh considerably less than the half which is not tapered. As, then, the tongue or lip of the container 31 is caused to sweep through the loose styli resting on the bottom of the container, it will catch, hold, separate out from the loose styli, and lift a single stylus resting in the recess provided by the slot 29 and lying upon the tongue or lip 31.

In Fig. 7 a stylus is shown as being so carried upwardly by the tongue or lip 31, the view being taken from within the container 15 looking outwardly through the slot 29. When, therefore, the heavier end of the stylus rests on and is supported by the lip or tongue 31 in the manner shown in Fig. 7, the stylus will remain seated upon the lip or tongue until the carrier shall have reached the limit of its upward motion with the slot 29 in alinement with the slot 10 as shown in Fig. 4. When this occurs, the stylus will roll by gravity out through the slot 10, over the shoulder 11 and down the inclined portion of the receiver 12, coming to rest against the upturned end 13 of the receiver 12. When, however, a stylus is caught on the tongue or lip 31 in the opposite position, that is to say, with its pointed end on and over the tongue or lip 31, and the container has been rotated to substantially the position shown in Fig. 3, the weight of the heavy end of the stylus will overbalance that of the lighter end resting on the tongue or lip 31, and the stylus will fall from the ledge or lip or tongue 31 back to the bottom of the container, as clearly indicated in Fig. 8. When so constructed, the device will deliver a stylus through the hole or opening 10, only when the heavier end thereof is resting on the tongue or lip 31, and when it does deliver or dispense a stylus, the pointed end of the stylus delivered thereby will always be adjacent the same edge of the receiver 12.

It will thus be seen that this feature of my invention is adapted for use in dispensing various articles, the center of gravity of which is on one side of a point midway between the ends thereof, whenever it is desirable to deliver such an article with a selected end always pointed in the same direction.

If, however, the tongue or lip 31 be made as long as the slot 29, the device will dispense a stylus for every operation, but the direction in which the sharp end points will not be uniform. It will deliver a stylus for every operation irrespective of the direction in which the sharpened end is pointed or directed. Such a construction is shown in the modified form illustrated in Figs. 9 to 15.

To operate the device shown in Figs. 1 to

8, and starting with the container empty, the operator removes the nut 19 and, grasping the knurled flange 22, withdraws the container 15 from the outer member 6. He then gives the removable head 21 a slight turn to free the pin 23 from the bayonet slot 24, whereupon the head 21 may be removed. He then places within the container 15 a quantity of loose styli, replaces the head 21 in the open end of the container, inserts the container in the outer member 6 with the stem 17 passing through the journal 9, and threads the nut 19 on to and over the threaded end 18 on the stem 17. He then grasps the handle 25 and turns the container 15 in an anti-clockwise direction, preferably until the pin 26 engages the stop 28 at the end of the slot 14. This position is shown in Fig. 1. In coming to this position the lip or tongue 31 will have passed through the bottom of the mass of needles in the container and agitated them, thus tending to cause the needles to come to positions in which their axes are parallel to each other and to the axis upon which rotates the container 15. The operator next turns the handle clockwise, until the pin 26 engages the stop 27 at the other end of the slot 14. This position is shown in Fig. 4. During this movement of the container, the lip or tongue 31 again sweeps through the supply of loose styli resting on the bottom of the container, but in opposite direction and again agitates the mass of styli. During this movement one at least of the styli will be caught by the lip 31, and will lie in the slot 29, resting against the cylindrical surface of the member 6 and against the forwardly inclined surface of the lip or tongue 31. This operation constitutes a selection of one stylus, a withdrawal of it from the mass of styli, and a carrying of it upwardly towards the shoulder 11 of the member 6. Before the lip or tongue 31 shall reach the position shown in Fig. 3, any stylus, other than the one lying against the inclined face of the lip or tongue 31, will roll off and fall to the bottom of the said container. If now the heavy end of the stylus so selected by the tongue or lip 31 rests on the tongue or lip 31, said stylus will remain there until the upper surface of the tongue or lip 31 is flush with the beveled edge 11 or shoulder of the slot 10, but when said last-mentioned position is reached, the stylus will roll by gravity over said edge 12 or shoulder 11 and down on to the receiver as shown in Fig. 4. If, however, the stylus, which is thus caught and retained on the tongue or lip 31, happens to be reversely positioned, that is to say, with the pointed end lying or resting on the tongue 31, then such stylus 32 will fall from the tongue 31, back to the bottom of the container before the said tongue or lip reaches the lower edge 11 of the slot 10 (as shown in Fig. 8), and no

stylus will be delivered or dispensed by the device upon that operation. When this occurs, the operation above described must be repeated until a stylus is caught by the lip 31 with its point lying over the cut away portion of the lip 31, whereupon such stylus will be delivered to the receiver.

The outer member 6, in the modification above described, is shown as completely 10 cylindrical. But this is not necessary. But substantially the lower half of the said member should be cylindrical to fit smoothly against the outer surface of the container which is adjacent the slot 29 therein, to close 15 the said slot 29 until the stylus is raised by the tongue 31 to a position where it may be delivered to the receiver, namely, when the tongue 31 is flush with the shoulder 11. But above the shoulder 11, the outer member 6 20 may be of any suitable shape, or the outer member may not extend above said shoulder 11 at all. In the modification shown in Figs. 9 to 15, the outer member 6' is in fact arc-shaped, and does not cover substantially 25 the upper half of the container. In this modified construction, the legs 4 are connected directly to the outer member 6', which member 6' comprises a substantially semi-cylindrical strip embracing a little 30 more than the lower half of the cylindrical container 15. This member 6' is preferably made of resilient metal and smoothly clasps around and retains the container 15. The container 15 is provided with substantially 35 the same slot 29, and with a lip or tongue 31' similar to that previously described. The outer member 6' is similarly provided with the same beveled edge or shoulder 11 over which the styli are delivered to the receiver 12, provided with an upturned end 40 13, all of which is substantially like the construction previously described. To prevent longitudinal movement of the container 15 with respect to the outer member 6', the 45 said member 6' is provided on one side with an upturned lug 34, the upper end of which is turned inwardly to hook over the inner edge of the flange 22' extending around the outer side of the removable head 21', which 50 forms the closure for the open end of the container 15. On the opposite side of the member 6' is a resilient upwardly turned lug 35 which prevents movement of the container 15 in the opposite direction.

55 The head 21' is similar to the head 21 of the modification previously described, but the pin and bayonet slot connection between the two may be omitted. The head 21' may be merely fitted into the open end of the container 15 and frictionally contained therein. The handle 25' may be mounted directly upon the outer cylindrical surface of the container 15, and its engagement with the bottom 27' of the slot 14' may serve to limit the 60 65 rotative movement of the container in its

clockwise direction. The back of the container 15 may be, and preferably is provided with a pin 26', and the engagement thereof with the stop 28', formed by the lug 35, will limit the rotative movement of the container in an anti-clockwise direction. As above indicated, the lip or tongue 31' in this modification may extend the whole length of the slot 29 and when so constructed the device will deliver a stylus every time it is operated irrespective of the direction in which the sharpened end is pointed, but it is to be understood, of course, that the said lip 31' may be made of substantially one-half the length shown, whereupon it will operate like the lip 31 of the form of my invention first above described.

The manipulation of the modified form of my invention shown in Figs. 9 to 15, inclusive is slightly different from that of the form shown in Figs. 1 to 8 inclusive and first above described. Starting with the container 15 empty, and referring particularly to Fig. 14, the operator will grasp the container 15 and tilt the bottom edge thereof next to the resilient finger 35 upwardly, as indicated in dotted lines in Fig. 14, thus moving the flange on the lid 21' out from under the overhanging hook of the lug 33. When tilted in this position and free from the lug 33, the container 15 is readily lifted vertically, slightly springing apart the upper ends of the resilient substantially semicircular outer member 6'. The operator will then remove the head or cover 21' and put a supply or stock of loose styli, or other articles to be dispensed into the container 15 and replace the head 21'. He will then replace the container 15 into the outer member 6', following the same steps as those followed by him in removing the container from the outer member 6' but in the reverse order.

He will then grasp the handle 25' and swing it in an anti-clockwise direction, preferably until it occupies the position shown in Fig. 9. In this position, the stop pin 26' will bear against the stop surface 28' of the resilient lug 35. The operator will then swing the handle in the opposite direction (clockwise, when referring to Fig. 9) and the tongue or lip 31 moving through the loose styli collected on the bottom of the container 15 will agitate and straighten out the loose styli; as previously referred to and will engage or select one stylus, and carry it upwardly, (as shown in Figs. 11 and 12) until the handle 25' strikes against the stop surface 27' of the slot 14' in the outer member 6'. In that position, the tongue 31' will be in a position shown in Fig. 12 flush with the shoulder 11 on the outer casing and the stylus will roll by gravity from the tongue 31', over the shoulder 11, on to the receiver 12, and will come to rest against the upturned end 13 thereof.

It will, of course, be understood that it may not always be necessary in turning the containers in an anti-clockwise direction to continue the movement in that direction until 5 the pin 26 of the modification shown in Fig. 1 actually brings up against the stop 28 or until the pin 26' of the modification shown in Fig. 10 brings up against the stop 28', particularly if there be a comparatively large number 10 of styli within the container. The stops 28 and 28' are, however, so arranged for convenience in operating the device and so that if there be but one stylus within the container, that the stylus will fall to the bottom 15 of the container when the container is swung in an anti-clockwise direction to the limit of its motion in that direction.

My invention is also adapted for use in a continuously operated machine for delivering 20 styli or similar articles with the sharp or lighter end thereof always in the same direction, as, for instance, when it is desired to so arrange them for packaging or for any other purpose. In Figs. 16 and 17 are shown two 25 forms of my device arranged for a continuous operation.

In Fig. 16, the device is substantially like the device shown in Figs. 1 to 8, but instead of being arranged for manual operation, a 30 pulley 36 is secured to the outer end of the stem or shaft 17. This pulley may be securely fastened to the shaft by a key 37 and nut 19' threaded over the threaded end 18 of the stem 17 and pressing squarely against 35 the face of the pulley 36. In Fig. 17, the pulley 36' also forms the flange of the head 21'. In other respects, the construction is substantially the same as that shown in Figs. 1 to 8.

In either of the modifications, last above described, and illustrated in Figs. 16 and 17, the container 15 is loaded with a large number 40 of styli and then the container is rotated continuously rather slowly in one direction by a belt (not shown) running around the pulley 36 or 36'. The container 16 in these 45 modifications is provided with a tongue or lip 31, such as is shown in Figs. 7 and 8. As the container is rotated, this tongue 31 sweeps through the quantity of styli resting 50 on the bottom of the container, agitates the contents thereof, and catching one stylus lifts it toward the receiver 12. If a stylus is caught on the lip 31 rests with the heavy end 55 against the lip 31, as shown in Fig. 7, then when the lip comes into registration with the slot 11 in the outer container, a stylus will roll by gravity out through the slot 10 over the edge 11 and come to a rest on the receiver 60 12. If, however, a stylus caught by the lip 31 is so positioned with respect thereto that the lighter end is over the lip 31 as shown in Fig. 8, then that stylus will fall from the lip 31 before the said lip comes into registration with the edge or shoulder 11 of the 65

slot 10. In this way, and in the arrangement shown in Figs. 16 and 17, one stylus will be delivered for every revolution of the carrier 15 provided the stylus is supported on the lip 31 in the manner shown in Fig. 7. 70

It is to be understood that in connection with the modification shown in Figs. 16 and 17, wherein the device might be used for other purposes than delivering styli for use in connection with the operation of a talking machine, the container 15 might be provided with a plurality of slots 29 and inwardly projecting tongues 31 suitably spaced from each other and extending completely around the surface of the inner container so that as each lip 31 comes into registration with the shoulder 11 of the outer member 6, it will deliver a stylus provided the heavy end thereof is resting upon the lip 31. 75 80 85

When a device embodying my invention is to be used to deliver a stylus or similar article, with a selected end always on the same side of the receiver, the inside longitudinal dimensions of the container, when closed by the removable head thereof, should be but slightly greater than the length of the stylus, or other article to be dispensed thereby, so that the said article when lifted by the tongue or lip will be substantially uniformly 90 95 longitudinally positioned with respect to the said tongue or lip.

It is, of course, to be understood that this device is primarily for the purpose of dispensing, one at a time, styli such as are used in connection with the operation of talking machines, but the device is not to be construed as being limited strictly thereto, because as above described, the construction may be readily changed and adapted for use 100 105 in connection with the dispensing of other elongated articles without departing from the spirit and scope of the appended claims.

Having thus described my invention, what I claim and desire to protect by Letters Patent is:

1. In a dispensing device the combination of a hollow container mounted for rotational movement and provided with a slot disposed parallel to the axis of rotation of said container, a stationary member having a cylindrical surface fitting against the outer surface of said container adjacent said slot and operative to close said slot at all times except when said container is at substantially 115 the limit of its rotational movement in one direction, said member being provided with a stylus receiver in alignment with the lower edge of said slot when said container is at its said limit of movement, a rigid tongue or lip carried by said container and projecting inwardly from the inner surface of said container and upwardly from said lower edge of said slot when said container is in said position, means to prevent the rotational move- 120 125 130

ment of said container above said point or position, and means to limit the rotational movement of said container in the opposite direction.

3. In a dispensing device the combination of a hollow container mounted for rotational movement and provided with a slot disposed parallel to the axis of rotation of said container, a stationary member fitting against the outer surface of said container adjacent said slot and operative to close said slot at all times except when said container is at substantially the limit of its rotational movement in one direction, said member being provided with a ledge in alinement with the lower edge of said slot when said container is at its said limit of movement, a tongue or lip carried by said container and projecting inwardly from the inner surface of said container and upwardly from said lower edge of said slot when said container is in said position, the width of said tongue being sufficient to support one only of the articles to be dispensed, means to prevent the rotational movement of said container above said point or position, and means to limit the rotational movement of said container in the opposite direction.

3. In a dispensing device the combination of a hollow container mounted for rotational movement and provided with a slot disposed parallel to the axis of rotation of said container, a stationary member operative to close said slot at all times except when said container is at substantially one limit of its rotative movement in one direction, said member being provided with a ledge in alinement with the lower edge of said slot when said container is at its said limit of movement in one direction, a tongue or lip carried by said container and projecting inwardly and upwardly from said lower edge of said slot when said container is at its said limit of movement, the length of said lip or tongue being substantially one-half the length of said article to be dispensed by said device.

4. In a dispensing device the combination of a stationary outer member having an inner cylindrical surface, a bearing carried by and disposed coaxially with the said outer member, a hollow container mounted within said member, a removable head forming a closure for said container, a journal carried by said container and mounted within said bearing, means to prevent longitudinal movement of said journal in said bearing, said outer member being provided with a ledge and said inner container being also provided with a slot the lower edge of which is adapted to be brought into alinement with said ledge on said outer member, the surface of said container around said slot being cylindrical and fitting against the said cylindrical surface of said outer member, and a tongue rigid with said container and project-

ing inwardly and upwardly from the lower edge of said slot in said container when the said lower edge of said slot and said ledge are in alinement.

5. In a device for dispensing elongated articles the center of gravity of which is on one side of a point midway between the ends thereof, the combination of a container adapted to be rotated freely on its axis and having a slot through the cylindrical surface thereof, an outer stationary member fitting against substantially the lower half of said container and providing a ledge in alinement or flush with which the lower edge of said slot is adapted to be brought by the rotation of said container, and a lip or tongue rigid with said container and extending upwardly and inwardly from the lower edge of said slot when the said lower edge thereof is flush or in alinement with said ledge, the length of said lip or tongue being substantially one-half the length of said article to be dispensed by said device.

6. In a device for dispensing styli and other substantially cylindrical articles, the combination with a hollow casing mounted for rotative movement about a fixed axis and provided with a slot therethrough parallel to said axis, a lip extending inwardly from the lower edge of said slot, and a stationary member having a cylindrical surface over which the outer surface of said casing around said slot slides during a portion of its rotational movement and also providing a ledge extending parallel to and substantially on the level of the axis of rotation of said casing, the width of said slot and lip respectively being a little greater than the diameter of the article to be dispensed and the length of said lip being substantially one-half of the length of said slot.

7. In a device for dispensing styli and other substantially cylindrical articles, the combination with a hollow casing mounted for rotative movement about a fixed axis and provided with a slot therethrough parallel to said axis, a lip extending inwardly from the lower edge of said slot, and a stationary member having a cylindrical surface over which the outer surface of said casing around said slot slides during a portion of its rotational movement and also providing a ledge extending parallel to and substantially on the level of the axis of rotation of said casing, the length of said slot being substantially equal to the full length of the interior of said casing, the width of said slot and lip respectively being a little greater than the diameter of the article to be dispensed, said lip extending from one end of said slot to a point substantially midway of the length of said slot.

8. In a device for dispensing styli and other substantially cylindrical articles, the combination with a hollow casing mounted

for rotative movement about a fixed axis and provided with a slot therethrough parallel to said axis, a lip extending inwardly from the lower edge of said slot, and a stationary member having a cylindrical surface over which the outer surface of said casing around said slot slides during a portion of its rotational movement and also providing a ledge extending parallel to and substantially on the level of the axis of rotation of said casing, said lip extending from one end of said slot to a point substantially midway of the length of said slot.

9. In a device for dispensing styli and other substantially cylindrical objects, the combination of a hollow rotatable cylindrical casing closed at both ends, having a slot therethrough parallel to the axis of said casing, extending for the full length of the interior of said casing and slightly longer than the article to be dispensed, a lip extending inwardly from the inner surface of said casing and from the lower edge of said slot, the width of said lip and the width of said slot being respectively a little greater than the diameter of the article to be dispensed, and a stationary member having a cylindrical surface fitting against substantially the lower half of said casing and providing a ledge substantially on a level with the axis of said casing.

10. In a device of the character set forth, a container having a cylindrical wall, a slide arranged to oscillate in said container concentrically to such wall, and a slot in the latter above the axis of said slide, adapted to receive and deliver a needle carried upwardly thereto by the edge of said slide.

11. A cylindrical container, a shaft arranged axially and horizontally therein, a slide carried by said shaft and arranged to sweep the interior of said container, the latter having a slot above the axial line of said shaft and adapted to receive and deliver a needle carried upwardly thereto by the edge of said slide.

12. In a device for dispensing styli and other substantially cylindrical objects, the combination of a hollow rotatable cylindrical casing closed at both ends, having a slot

therethrough parallel to the axis of said casing, extending for the full length of the interior of said casing and slightly longer than the article to be dispensed, a lip extending inwardly from the inner surface of said casing and from the lower edge of said slot, the width of said lip and the width of said slot being respectively a little greater than the diameter of the article to be dispensed, a stationary member having a cylindrical surface fitting against substantially the lower half of said casing and providing a ledge substantially on a level with the axis of said casing, and a receiver extending outwardly and downwardly from said ledge.

13. In a device for dispensing styli and other substantially cylindrical objects, the combination of a hollow rotatable cylindrical casing closed at both ends, having a smooth interior surface, a single slot therethrough parallel to the axis of said casing extending for the full length of the interior of said casing and slightly longer than the article to be dispensed, a lip extending inwardly from the inner surface of said casing and from the lower edge of said slot, the width of said lip and the width of said slot being respectively a little greater than the diameter of the article to be dispensed, a stationary member having a cylindrical surface fitting against substantially the lower half of said casing and providing a ledge substantially on a level with the axis of said casing, and a receiver extending outwardly and downwardly from said ledge.

14. In a device for dispensing articles, a container mounted to rotate about a fixed axis and provided with a slot parallel to said axis, said container being provided with a lip extending inwardly from the lower edge of said slot, the width of said slot being less than twice the diameter of an article to be dispensed, the width of said lip being sufficient to support one only of said articles, and the length of said lip being substantially one-half the length of said article.

In witness whereof, I have hereunto set my hand, this 14th day of November, 1921.

WILLIAM D. LA RUE.
